(57) **CLAIM**

The ornamental design for a ink stamp, as shown, and, described.

DESCRIPTION

FIG. 1 is a top, front perspective view of a ink stamp, showing my new design.

FIG. 2, is a top plan view thereof, and;

FIG. 3 is a bottom plan view thereof.

The broken lines shown in the drawings represent environmental structure and form no part of the claimed design.

1 Claim, 3 Drawing Sheets
